FISHING LURE

Kenneth H. Knight, 1247 N. 43rd St., Milwaukee, Wis.

Filed Feb. 26, 1962, Ser. No. 68,962

Term of patent 7 years

(Cl. D31—4)

Fig. 1

Fig. 3

FIG. 1 is a side elevation of a fishing lure, showing my new design;

FIG. 2 is a bottom plan view thereof; and

FIG. 3 is an end elevation thereof.

I claim:

The ornamental design for a fishing lure, as shown.
